G. M. LATIMER

BURNER

Filed Apr. 15, 1922

UNITED STATES PATENT OFFICE.

GEORGE M. LATIMER, OF CARPINTERIA, CALIFORNIA.

BURNER.

Application filed April 15, 1922. Serial No. 553,104.

To all whom it may concern:

Be it known that I, GEORGE M. LATIMER, a citizen of the United States, residing at Carpinteria, in the county of Santa Barbara 5 and State of California, have invented new and useful Improvements in Burners, of which the following is a specification.

This invention relates to burners and more particularly to retorting burners.

10 An object of the invention is to provide a burner adapted to generate gaseous fuel from liquid fuel and to provide for the continued generation of the gas as the liquid fuel passes through a retorting member. 15 Another object is to provide an improved construction of burner whereby the flames from the burner retort will be evenly deflected from the burner outlet to secure a uniform distribution of the heat produced 20 by the generation of the fuel.

One embodiment of the invention is herein described and illustrated in the accompanying drawings, in which—

Figure 1 is a side elevation of a preferred 25 construction of the burner in combination with the supply reservoir.

Fig. 2 is a plan of the deflector plate.

Fig. 3 is a section on line 3—3 of Fig. 2.

Fig. 4 is a section through the retort pipe 30 and its discharge tip on line 4—4 of Fig. 1.

The illustrated embodiment of my present invention comprises a fuel supply pipe 2 of suitable dimensions, and this is connected to a main control valve 3 from which leads 35 a small conduit or tube 4 to a pressure chamber or reservoir 5 which is designed to contain liquid fuel, such as kerosene, under pressure which may be maintained at the desired degree by means of a pump 6 40 associated with the reservoir.

Preferably, directly mounted upon the supply pipe 2 is a pan 7 shown in plan as of elliptical form, although it may be of other shape if desired. The pan is provided with an upwardly curved bordering flange 8, and the pan is arranged lengthwise upon the pipe 2 to which it is attached as by means of clips 9.

At one end of the pipe 2 is an upturned 50 portion 10 and this in turn is provided with a horizontally extending retort member or tube 11 which may be closed at the outer end by cap 12.

A feature of the present invention consists of means for withdrawing from the 55 retort tube 11 a stream of substantially clean liquid fuel, that is fuel which is free of sediment. To secure this, there is arranged in the retort tube 11 a discharge nipple 13 which extends upwardly into the tube as 60 shown in Fig. 4, to a level considerably above the bottom of the tube so that in starting combustion at the burner when the valve 3 is opened, the liquid fuel passes from the upper portion of the retort member 11 65 into the upper end of the nipple 13 from which it is discharged vertically down upon the central flat portion of the pan 7 which constitutes a deflector for the flame of combustion. The nipple 13 is shown as consisting of a tube having a small axial port to produce a relatively fine discharge stream or jet, and the nipple is secured in a bushing 14 which is screwed into the bottom of the retort member 11. 70

After a small quantity of liquid fuel has been discharged into the pan 7, it is ignited by a match or other means, and the combustion of this initial supply heats the retort member 11 and therefore the fuel 80 therein, so that the latter is discharged in a heated condition through the nipple 13 straight down upon the pan 7. The flames of combustion are diverted uniformly from the point of impact of the jet of fuel against 85 the bottom of the pan 7 by reason of the perpendicular direction of the stream as to the bottom of the pan.

Various changes and modifications may be made without departing from the spirit of 90 the invention as claimed.

What is claimed is:

1. In an oil burner, a fuel pipe, a pan having a surrounding, upwardly curved flange, means for attaching the pan in a position 95 upon the top of the pipe, and a retort attached to the said pipe and disposed above the pan and having a nipple arranged to discharge a stream of fuel perpendicularly upon the pan. 100

2. In an oil burner, a fuel pipe, a pan having a surrounding, upwardly curved flange, means for attaching the pan in a position upon the top of the pipe, and a retort attached to the said pipe and disposed above 105 the pan and having a nipple arranged to

discharge a stream of fuel perpendicularly upon the pan, said pan being elliptical in plan and arranged lengthwise on the pipe.

3. In an oil burner, a flat pan having an upturned flange, a retort pipe connected with a supply pipe to which said flat pan is secured, and a nipple extending through a bushing in the bottom of said retort pipe

and projecting upwardly from its bottom surface, said nipple being arranged to discharge clean liquid fuel directly upon the flat portion of said pan.

In testimony whereof I have signed my name to this specification.

GEORGE M. LATIMER.
